UNITED STATES PATENT OFFICE

CHARLES J. MCKENNA, OF NEWARK, NEW JERSEY, ASSIGNOR TO ATLAS SUPPLY COMPANY, OF NEWARK, NEW JERSEY, A CORPORATION OF DELAWARE

DESIGN FOR A COMBINED TESTING APPARATUS AND STOCK STAND

Application filed September 24, 1931. Serial No. 41,212. Term of patent 7 years.

To all whom it may concern:

Be it known that I, CHARLES J. MCKENNA, a citizen of the United States, residing at Newark, in the county of Essex and State of New Jersey, have invented a new, original, and ornamental Design for Combined Testing Apparatus and Stock Stands, of which the following is a specification, reference being had to the accompanying drawings, forming part thereof.

Figure 1 is a perspective view of a combined testing apparatus and stock stand, showing my new design, and

Figure 2 is an end view of the same.

I claim:

The ornamental design for a combined testing apparatus and stock stand, as shown.

CHARLES J. MCKENNA.
